(57) CLAIM

The ornamental design for a cheerleading glove, as shown and described.

DESCRIPTION

FIG. 1 is a rear elevational view of a cheerleading glove
showing my new design;

FIG. 2 is a front elevational view of the cheerleading glove of
FIG. 1;

FIG. 3 is a left side elevational view of the cheerleading glove
of FIG. 1;

FIG. 4 is a right side elevational view of the cheerleading glove of FIG. 1;

FIG. 5 is a top plan view of the cheerleading glove of FIG. 1;
and,

FIG. 6 is a bottom plan view of the cheerleading glove of FIG.

The broken lines shown in FIG. 6 represent the portions of the design which form no part of the claim.

The present invention relates generally to cheerleading gloves, and more specifically, to cheerleading gloves with tassels, wherein the glove finger tips are removed to expose the fingers.
